CLAIM

The ornamental design for accessory hanger for awnings, as shown.

DESCRIPTION

FIG. 1 is a left side, top and front perspective view showing my new design for an accessory hanger for awnings;

FIG. 2 is a front elevational view thereof, the undisclosed rear being substantially the same;

FIG. 3 is a left side elevational view, the end opposite being a mirror image; and,

FIGS. 4 and 5 are respectively top and bottom plan views.

FIG.1.

FIG. 4.

FIG. 2.

FIG. 3.

FIG. 5.
